UNITED STATES PATENT OFFICE.

WILLIAM H. SCOTT, OF ST. LOUIS, MISSOURI, ASSIGNOR TO THE CONTROLLER COMPANY OF AMERICA, OF ST. LOUIS, MISSOURI, A CORPORATION OF MISSOURI.

COIN-CONTROLLED LOCKING MECHANISM.

SPECIFICATION forming part of Letters Patent No. 728,995, dated May 26, 1903.

Application filed August 11, 1902. Serial No. 119,283. (No model.)

To all whom it may concern:

Be it known that I, WILLIAM H. SCOTT, a citizen of the United States, residing at the city of St. Louis, State of Missouri, have invented a certain new and useful Improvement in Coin-Controlled Locking Mechanisms, of which the following is a full, clear, and exact description, such as will enable others skilled in the art to which it appertains to make and use the same, reference being had to the accompanying drawings, forming part of this specification, in which—

Figure 1 is an elevation showing the casing in section, the operating parts being shown in locking position in full lines and in unlocking position in heavy dotted lines, the light dotted lines showing the position of the coin and the locking-lever after the coin has been inserted and before the receiver has been lifted from the suspension-hook. Fig. 2 is a front elevation. Fig. 3 is a plan view on line 3 3, Fig. 1, the casing being shown in section. Fig. 4 is a view of the character of Fig. 1 and illustrating a modification, the parts being shown in locking position in full lines and in unlocking position in dotted lines; and Fig. 5 is a fragmentary view illustrating a further modification.

My invention relates to coin-controlled locking mechanisms, and more particularly to telephone-locks of the character indicated, my object being to provide an efficient construction which can be cheaply manufactured and to reduce friction in the operation of the apparatus.

To these ends, and also to improve generally upon devices of the character indicated, my invention consists in the various matters hereinafter described and claimed.

Referring now more particularly to the drawings, 1 indicates a telephone-box, which can be of any suitable construction, and 2 represents the customary suspension-hook for the telephone-receiver 3. A box or casing 4 is secured to the wall or other suitable support to extend at the side of said telephone-box in such manner that the hereinafter-described locking plate or disk lies over said suspension-hook, said casing containing the

hereinafter-mentioned locking mechanism 50 and being provided with a coin-raceway 6. A suitable wall of the casing is provided with a slot 7, through which a locking plate or disk 8 can project, said plate or disk being prevented from passing completely through the said slot 55 in any appropriate manner. In the construction shown in Fig. 1 the casing is provided with an overhanging lip 9 in the path of movement of the locking-disk, the length of the slot 7 thus being less than the diameter 60 of the said disk. The side walls 10 of the casing, the top wall 11 thereof, and a guiding-wall 12 upon the side of the disk opposite the said wall 11 lie upon four sides of the locking-disk and thus guide the same in its 65 movement, the said guiding-wall 12 being either vertical or inclined toward said slot, so that the said locking-disk tends to fall into locking position by reason of its own weight. Pivoted intermediate said locking-disk and 70 the discharge end of the raceway 6 is a locking-lever 13, which has a locking-arm 14 extending from one side of its pivot and a coin-receiving arm 15 extending from the other side thereof and projecting under the discharge end of the raceway in such position that it lies in the path of an inserted coin. A stop-arm 16 is also included in the said lever and so extends therefrom that when the lever is rocked upon its pivot its free end passes 75 through an opening 17 in the guiding-wall 12 and engages the periphery of the locking-disk 8. The locking-disk normally falls into locking position by reason of its own weight, and the locking-arm 14 of the locking-lever 80 overbalances the other arms thereof, so that said lever normally lies in locking position with its locking-arm intermediate its pivot and the locking-disk and its coin-receiving arm below the raceway, all as shown in full 85 lines in Fig. 1. The receiver suspension-hook 2 lies against the periphery of the locking-disk 8, and such hook is therefore locked against upward movement. When a coin is inserted in the raceway 6, it drops upon the 90 coin-receiving arm 15 of the locking-lever and throws the lever into such position that the locking-arm 14 is carried out of locking 95

position with relation to the disk 8, this movement of the locking-lever being limited by reason of engagement of the stop-arm 16 against the periphery of the locking-disk 8 and such engagement taking place before the locking-lever has moved sufficiently to permit the deposited coin A to pass from the raceway 6. The locking-disk is now free to be moved, and as soon as the receiver is lifted from the suspension-hook the usual spring connected to the said hook forces the same upwardly and throws the locking-disk inwardly, as shown by the light dotted lines in Fig. 1, and as said disk moves inwardly it passes beyond the end of the stop-arm 16, and thus permits the deposited coin to move the locking-lever sufficiently to allow the coin to be discharged. When the receiver is again placed upon the suspension-hook, said hook falls, and the support being thus removed from under the locking-disk 8 said disk falls into locking position, and thus permits the locking-lever 13 to return to normal position, the overbalancing arm 14 having rested upon the disk 8 during the time that the parts were in unlocking position. The stop-arm 16 and the locking-arm 14 of the locking-lever extend about the inner side of the disk 8 when the parts are in unlocking position, and thus coöperate with the walls 10, 11, and 12 to form a pocket within which the locking-disk is confined.

The locking-plate 8 can of course be of any suitable shape; but I prefer to employ a disk, as under the lifting action of the receiver suspension-hook such disk can roll along the guiding-wall 12, and friction between the locking-plate and its guiding member is thus avoided.

The device is extremely simple in its construction, and the locking-lever is the only part which has to be fastened upon the casing, the locking disk or plate 8 being merely dropped into its raceway between walls 10, 11, and 12.

In the modification illustrated in Fig. 4 I have shown the walls 10^a, 11^a, and 12^a arranged to produce a vertical raceway for the locking-plate 8, the remaining parts of the device being constructed in substantially the same manner as shown in Fig. 1. In this construction the raceway for the locking plate or disk and the slot through the wall of the casing are sufficiently wide to permit passage

of the said locking-plate, and the plate is prevented from dropping from the said raceway by means of pins 18 across the ends of the slot.

In Fig. 5 I have shown a vertically-movable locking-plate 8^a, provided with a slot 19, through which a guide-pin 20 extends, said

pin serving to prevent the locking-plate from falling from the casing.

I am aware that minor changes in the construction, arrangement, and combination of the several parts of my device may be made and substituted for those herein shown and described without in the least departing from the nature and principle of my invention.

Having thus described my invention, what I claim as new, and desire to secure by Letters Patent, is—

1. In a mechanism of the character indicated, a casing having a raceway open at its inner end, a locking member freely movable in said raceway, a pivoted locking-lever at the inner end of said raceway and having a locking-arm adapted to coöperate with said locking member and a stop-arm which lies at the side of and away from said locking member when said lever is in locking position and is adapted to engage said locking member to limit the pivotal movement of said lever when said lever is rocked from locking position, the arms of said lever extending across and closing the free end of said raceway when said lever is in unlocking position, and means for causing a deposited coin to rock said lever from locking position, the stop-arm-arresting portion of said locking member having movement to carry the same out of stop-arm-arresting position; substantially as described.

2. In a mechanism of the character indicated, a casing having a raceway open at its inner end and provided with a side wall having an opening therethrough, a locking member movable in said raceway, a pivoted locking-lever at the inner end of said raceway and having a locking-arm adapted to coöperate with said locking member and a stop-arm which lies at the side of and away from said locking member when said lever is in locking position and is adapted to move through said wall-opening and engage said locking member to limit the pivotal movement of said lever when said lever is rocked from locking position, the arms of said lever extending across and closing the free end of said raceway when said lever is in unlocking position, and means for causing a deposited coin to rock said lever from locking position, the stop-arm-arresting portion of said locking member having movement to carry the same out of stop-arm-arresting position; substantially as described.

In testimony whereof I hereunto affix my signature, in the presence of two witnesses, this 9th day of August, 1902.

WILLIAM H. SCOTT.
